UNITED STATES PATENT OFFICE

WASHINGTON B. WILLIAMS, OF KENWOOD, MARYLAND

COAL CONVEYER

Application filed July 2, 1929. Serial No. 375,447.

The object of this invention is primarily to enable a motor operated delivery vehicle to stand parallel with the street curb and to discharge its contents into a conveyer which extends at right angles to the curb and leads into a building or other place of storage, the conveyer consisting broadly of sections which may be carried in knock-down or folded form on the sides of the vehicle and which, when set up, are connected serially with each other and driven one from another and from a supplemental shaft operated by the power plant of the delivery vehicle.

Reference will be had to the accompanying drawings forming a part of this specification and in which like reference characters designate corresponding parts throughout the several views, in which

Fig. 1 is a view in side elevation of the invention,

Fig. 2 is a top plan view thereof, the chute being shown in dotted lines,

Fig. 3 is a longitudinal vertical sectional view through adjoining end portions of two conveyer sections,

Fig. 4 is a top plan view thereof, parts being broken away and others shown in section,

Fig. 5 is a transverse vertical sectional view taken through line 5—5 of Fig. 3,

Fig. 6 is a transverse vertical sectional view through a section of the conveyer in collapsed or folded position,

Fig. 7 is a transverse vertical sectional view through the conveyer showing the feed chute and a fragment of the driving shaft,

Fig. 8 is a vertical sectional view through one of the conveyer rollers on the line 8—8 of Fig. 7,

Fig. 9 is a transverse vertical sectional view through one side of the transporting truck body showing conveyer sections stored on the side thereof for transportation,

Fig. 10 is a side elevation of a modified form of coupling driving gearing for adjacent sections, and

Fig. 11 is a transverse vertical sectional

view therethrough taken on line 11—11 of Fig. 10.

Referring to the drawings, reference numeral 2 designates the body of a motor truck or the like in which the coal or other material is transported, 3 the vehicle axle, and 4 the traction wheels thereof. The said body 3 is provided with the usual discharge spout 5 from which the coal or like material is discharged into a chute 6 and fed by gravity therefrom into the conveyer. From the motor truck leads a supplemental drive shaft 7 composed of universally jointed sections, this shaft being driven from the power plant of the motor truck 8 and driving the conveyer.

The conveyer is composed of coupled sections, each consisting of sheet metal side channels 9, to the upper end lower flanges 10 of which are hinged metal wings 12 by 70 means of hinges 14. Journaled between the webs of the side channels 9 are rollers 16 around which the endless conveyer belts 15 pass. The conveyer sections are alike, except at the end of the first section to 75 which power from the motor truck is applied. At this end, the roller 16 has its ends formed with trunnions 17 suitably journaled in said side plates or channels 9 and the bore 18 of this roller is polygonal 80 in cross section to drivingly receive the polygonal drive shaft end section 19. This shaft section 19, when the conveyer is set up being merely inserted into the bore of the said roller 16. The rollers at the other 85 end of the first conveyer section and all the other end rollers, as indicated by the numeral 20, are similar and each has trunnions 21 journaled in bearings 22 on the inner faces of the side channel plates 9 and 90 spur gears 24 on said trunnions 21 at both ends of the rollers.

In order that one conveyer section will transmit power to the following conveyer section to drive the same, an insertible spur 95 gear 25 journaled on a swinging arm 26 and adjustably carried by each hinged side wing plate 12 is provided. When the conveyer sections are connected together, as by any suitable fastening means 27, such 100

as hooks or other detachable devices, a spur gear 25 is entered between adjacent spur gears 24 or adjacent conveyer sections into mesh with such gears 24, this being permitted by the slot and pin mountings 28 and 29 respectively. A spur gear 25 is provided at each end of all of the conveyer sections, except the first such section, but on opposite sides of the conveyer belt of each section, and the said first conveyer section has only one such spur gear 25 which is only at its end opposite to the driving roller 16. The purpose of these spur gears is to drivingly couple the belts of adjacent sections, and since the conveyer sections are reversible, that is, they may be turned end for end or top for bottom, one of the spur gears 25 of one or the other conveyer sections is always available for coupling the sections together. Nuts 30 may be employed to retain the spur gears 25 in meshed relation with the spur gears 24. The spur gear 25 which is not utilized for drivingly coupling the gears 24 is swung to an inoperative position where it may be secured by tightening the nut 30 or may hang by gravity in that position.

The side channels 9 of each section are spaced apart by cross rods 35, and other rollers 36 are suitably journaled at intervals between said channel plates 9 to prevent sagging of the belts 15 of the various sections when under load. The flanges 10 of the channel plates 9 terminate short of the ends of the sections to permit insertion of the spur gears 25 between the gears 24, and these flanges are supposed to extend close enough to the belts to prevent material entrance of the coal or other material conveyed from leaking over the side edges of the belts. Any suitable means may be employed for holding the side wing plates 12 unfolded in vertical position, such as the cross braces 38 having opposite forked ends 39 which engage over the edges of said plates 12. The cross braces which hold the bottom wing plates 12 may be placed upon the ground and the conveyer sections placed thereon. Instead of these separate cross braces 38, another form of brace which is permanently carried by the conveyer sections may be adopted.

The conveyer sections are adapted to be folded and carried by brackets on the side or sides of the motor truck (see Fig. 9), as many sections being carried as will be needed, but a first section always being carried. When the wing plates 12 are collapsed, they fold inwardly upon the belt as in Fig. 6, the gears 25 being swung to the position shown and folded down with the wing plates 12. Thus it will be seen that when folded each conveyer section forms a box like structure, virtually without projections, so that they may be stacked on the side of the mo-

tor truck body, and receive rough handling without damage resulting thereto.

In the modified form illustrated in Figs. 10 and 11, a boxing is provided at each end of the sections, except the power receiving end of the first section, which is the same as in the preferred form, with a boxing 40 between the flanges 10' of the side channels 9'. Wing plates 12' are hinged at 14' to these flanges 10' as in the other form. The rollers 20' for the conveyer belt 15' have trunnions 21' journaled in the boxings 40 and upon these trunnions are fixed spur gears 24' with which mesh the coupling spur gears 25' swingingly mounted on arms 26'. These arms 26' have slots 28' receiving pins 29' provided with tightening nuts 30' permitting entering the gears 25' into mesh between the gears 24' or permitting the same to be swung out of such meshing relation. It is immaterial if a spur gear 25' remains in mesh with one of the spur gears 24' when such gear 25' is not employed for drivingly coupling the conveyer sections.

The wing plates 12 or 12' not only form supports to keep a sagging conveyer belt well off the ground, but serve to retain the coal or other material on the belt without spilling over the sides of the conveyer, and when folded over upon the belt completely inclose all parts that might be injured through careless handling of the conveyer sections.

What is claimed:

1. The combination with a motor operated delivery vehicle, of a conveyer constructed of serially related and driven sections, means for driving the conveyer from a power shaft of said vehicle, each section being constructed to fold into box-like form with no projecting moving parts, and means for carrying collapsed sections on the side of the vehicle in stacked relation. 100

2. The combination with a motor operated delivery vehicle, of a conveyer composed of sections serially arranged on the ground and each successive section driven from a preceding one, and means for driving the first section from a power shaft of the vehicle, any of the sections being reversible top for bottom. 110

3. The combination with a motor operated delivery vehicle, of a conveyer composed of sections serially arranged on the ground and each successive section driven from a preceding one, and means for driving the first section from a power shaft of the vehicle, any of the sections being reversible top for bottom, and any of the sections except the first being reversible end for end. 120

4. A conveyer, comprising a frame, a conveying element arranged therein, upper side members hinged to the frame and foldable from a plane at right angles to that of the conveyer element to one parallel therewith, 130

and similar lower side members the upper side members serving to confine the conveyed material and the lower ones serving to support the conveyer element off the 5 ground.

5. In a conveyer, the combination of a frame, an endless conveyer element arranged therein, a pair of spaced parallel side members hinged to the upper side of 10 the frame and another pair of parallel side members hinged to the under side of the frame, the members of each pair being foldable toward each other into the same plane and into a plane parallel with the endless 15 conveyer element, either pair of side members being adapted to support the frame and its associated parts or to confine the material being conveyed.

In testimony whereof I affix my signature.
